Application March 18, 1933, Serial No. 661,464
In Switzerland and Germany March 21, 1932

35 Claims. (Cl. 197—128)

The present invention relates to typewriters and more particularly to a device for use on typewriters for superposing and adjusting an upper sheet in front of a journal sheet already located in the machine by means of feed rollers arranged above the platen.

In the hitherto known devices of this kind it was necessary for the purpose of introducing and adjusting the upper sheets to carry out a considerable number of manipulations. The mode of adjustment was complicated and tedious and demanded particular attention on the part of the operator.

These defects are avoided according to the invention principally by providing for the purpose of adjusting the upper sheet to the desired line position, a control member having a selector disc or dialling disc, which control member is operatively connected with the feed rollers.

Furthermore, according to the invention, the device may advantageously be constructed in such manner that the superposed sheet is moved automatically by means of feed rollers operatively connected with a spring motor and that the said superposed sheet during line spacing operations is automatically ejected as desired, or for the purpose of being continuously typed upon line by line together with the journal sheet can be moved forward step by step.

A preferred constructional form of a device according to the invention is illustrated by way of example in the accompanying drawings, in which:

Fig. 1 is a front elevation of the device,

Fig. 2 is a rear elevation of the device,

Fig. 3 shows to a larger scale a front elevation of the control member together with the transmission parts and the spring motor,

Figs. 4 to 7 show details of the latter,

Fig. 8 is an end elevation of the device,

Fig. 9 is a plan of Fig. 8,

Fig. 10 is a perspective view of the platen together with a journal sheet and a superposed sheet,

Fig. 11 is a cross section taken through the platen and the appertaining paper feeding and guiding members in the position for the introduction of a journal sheet,

Fig. 12 is a similar cross section to Fig. 11, but shows the parts in the position for the introduction of a sheet which is to be superposed, and

Fig. 13 shows a detail of Fig. 12 in end elevation.

In the drawings the known parts of the type-

writer are only shown so far as is essential for the comprehension of the invention.

Referring to the drawings:

The device is detachably mounted by means of lateral supports 1 and 2 on the spindle 60 of the platen S between the ends of the platen and the bearings of the said spindle 60. Each support 1 and 2 respectively is provided with a pin 1a and 2a respectively, which rests in an arm 3 and 4 respectively fixed to the carriage of the typewriter and provided with a slot for the reception of the said pin (Figs. 1 and 8). On the pin 1a of the one support 1 an adjusting knob 5 is mounted which can be pushed outwards against the action of a spring 6. In the operative position the said knob passes below a pin 3a projecting laterally on the arm 3, and thereby locks the whole device on the carriage of the typewriter. In order to detach the device it is only necessary to draw out the adjusting knob and lift out the device, whereupon the machine can be used as an ordinary typewriter. After releasing the adjusting knob 5 it is also possible to flap the device over towards the rear.

Between the supports 1 and 2 a quadrilateral supporting bar is fixed which carries the guiding device for the superposed sheet. The said device is constituted primarily by a feed plate 8, the lateral edges of which are bent round towards the front. Between the said bent lateral edges a front guide plate 9 is mounted, the lower end 9a of which projects between the feed rollers towards the platen S.

Behind the feed plate 8 a guide plate 10 is arranged which serves for ensuring that the journal sheet J is correctly introduced in such manner that upon its introduction it passes properly around the platen S and does not enter the space between the feed and guide plates 8 and 9 (Figs. 11 and 12). The guide plate 10 is pivoted by means of two upwardly extending projections 10a to arms 11 which are fixed on a rod 12 mounted longitudinally of the supporting bar 7. At the left hand end of the rod 12 a crank 13 is fixed to which a tension spring 14 anchored to the supporting bar 7 is attached. The guide plate 10 is provided in the middle with a guide flap 10b having a longitudinal slot 10c into which a projection 15 fixed to the supporting bar 7 projects and limits the movement of the said guide plate 10. In the position shown in Figs. 2 and 11 the crank 13 has been turned over towards the rear into the position indicated by chain dotted lines, so that the guide plate 10 is located in the lower position and projects through the inter-

mediate space between the upper edge of the line spacing indicator **Z** arranged in front of the platen **S** and the lower edge **9a** of the guide plate **9**. If, now, the journal sheet **J** as a result of the 5 rotation of the platen has arrived at the height of the upper edge of the line spacing indicator **Z**, it strikes against the guide plate **10** and is guided by the latter properly around the roller. When the crank **13** is turned back into the position shown in Fig. 12 in chain dotted lines and in Fig. 13 in full lines, the guide plate **10** moves upwards and passes behind the feed plate **8**. The guide plate **10** is provided with two lateral projections **10e** (Fig. 1), which at the same time render possible an exact determination of the height 10 of the lines of the journal sheet **J**.

At the lower end of the feed and guide plates **8** and **9** the feed rollers **17**, **18** for the superposed sheet **K** are arranged, which latter is introduced 15 into an auxiliary lower paper feed member **16**. The feed rollers **17** and **18** arranged in pairs are fixed on axles **19** and **20** which are journalled by means of bearing brackets longitudinally on the supporting bar **7**, the bearing brackets **23** of the 20 front axle **19** being fixed, whilst the bearing brackets **24** of the rear axle **20** are adapted to swing and are drawn forwards by the action of a spring **25**. At the left hand end of the two axles pinions **21** and **22** which are in engagement with 25 one another are fixed. As a consequence of this both the pairs of rollers rotate correspondingly so that absolutely reliable introduction and forwarding of the account sheet **K** is ensured.

The drive of the feed rollers **17** and **18** is illustrated in Figs. 1 to 9. On the right hand end of the supporting bar **7** at the rear side thereof a supporting plate **27** projecting over the right hand end is fixed, which is provided with a central projection **27a** (Figs. 2 and 3) to which a forwardly projecting axle **28**, having a control member **29** rotatably mounted upon it, is fixed. This control member **29** is provided with a selector device **29a**, **29b**, which is constructed similarly to the usual selector discs or dialling discs provided on 40 automatic telephone apparatus. The control member **29** comprises an upper apertured disc **29a** having a number of finger holes **29b**, and a number disc **29c** located below the first named disc and rigidly connected therewith, the said number disc bearing numbers, for example 1 to 20, 45 located below the finger holes. On the outside of the support **2** an upwardly projecting curved stop arm **30** is fixed on which the finger strikes when the apertured disc **29a** and consequently the 50 whole control member **29** is rotated. On the rear side of the disc **29c** a bevel wheel **31** is fixed which engages with a considerably smaller bevel wheel fixed at the upper end of a shaft **33** mounted on the supporting plate **27**. The shaft **33** is 55 provided at its lower end with a similar bevel wheel **34** which engages with a bevel wheel **35** fixed at the right hand end of the roller axle **19** (Figs. 1 and 3). On the roller axle **19** a cord roller **36** is fixed. Above the cord roller **36** a spring 60 motor is fixed on the supporting plate **27**, which spring motor is provided with a spiral spring **38** enclosed in a housing **37** constructed in the form of a cord drum. The cord **39** is wound up at the one end on the said cord drum **37** and at the other 65 end to the cord roller **36**. As soon as the driving axle **19** is set in rotation by means of the control member **29** the cord unwinds itself whilst tensioning the spring **38** from the cord drum **37** and winds itself up on the cord roller **36**, and mean- 70 while the rotating feed rollers **17** and **18** draw in 75

the account sheet **K** inserted from above between the guide members and roll it round the platen **S**. When the control member **29** is released, the spring **38** becoming untensioned winds up the cord **39** again on the cord drum **37** and thereby turns the feed rollers **17** and **18** in the opposite direction, whereby the superposed sheet is conveyed back again, i. e. is ejected.

The disc **29c** is provided on its rear side with pins **29d** arranged at uniform distances from one another on a circle concentric to the axle **28**. The number of pins **29d** is equal to the number of finger holes **29b** in the apertured disc **29a** and to the number of figures on the disc **29c** rigidly connected with the said apertured disc **29a**. Into the path of motion of the said pins **29d**, which are bevelled off at their outer ends (see Fig. 4), a locking pawl **40** projects when in the normal position, the said pawl being mounted on a pawl carrier **42** (Figs. 3 and 4) so as to be capable of swinging around a pin **41**. The locking pawl **40** is maintained by the action of a tension spring **43** in the said position, so that every time when, on the rotation of the control member **29**, a pin **29d** slides over the said pawl, the latter can be pressed 25 downwards by the pin. The pawl carrier **42** constitutes a vertical projection of a bell crank lever **44** which is mounted at its fulcrum **45** so as to be capable of swinging, on the rear side of the supporting plate **27** and the longer lever arm **44a** of which projects downwards. With the shorter arm **44b** of the said bell crank lever the one end of a tension spring **46** engages, the other end of which is anchored to the supporting plate **27**. At the front end of the pawl carrier **42** an auxiliary locking pawl **40h** is fixed which is normally not located in the path of motion of the pins **29d**. If, however, the angle lever **44** is swung against the action of the spring **46** in the direction of the arrow I (Fig. 3), then the locking pawl **40** moves 40 out of the path of motion of the pins **29d** and the auxiliary locking pawl **40h** moves into the said path. When the lever **44** is swung in the direction of the arrow II the locking pawl **40** also moves upwards out of the range of the pins **29d**, 45 and the control member **29** which has been turned forwards into an operative position by means of the selector device can turn back under the action of the pull of the cord **39** into the position of rest without being arrested by the locking pawls **40** and **41** respectively. During this operation a pin **47** on the rear side of the control member **29** strikes against a buffer member **48** which is fixed to the supporting plate **27** and which 50 damps the impact effect and maintains the control member **29** in the initial position.

Below the locking pawls a locking lever support **49** is fixed on the supporting plate **27**, to which locking lever support a locking lever **50** is pivoted the one upwardly curved end **50a** of 55 which is acted upon by a tension spring **51** and bears in the initial position against a projection **29e** of the disc **29c**, whilst the other end **50b** of the said lever is constructed in the form of a locking hook and rests upon the lever arm **44a**, 60 the said end coming into engagement behind the latter under the action of the tension of the spring **51** as soon as the control member **29** is turned out of its initial position.

At the lower end of the supporting plate **27** a horizontal bolt **52** is arranged so as to be slidable, the front end of which bolt is bent over the lever arm **44a** so that the latter bears against the shoulder **52a** thus formed (see Fig. 7). To the 65 other upwardly bent end of the bolt **52** a tension 70

75

spring 53 is fixed, which is anchored by means of a guide pin to the supporting plate 27 and tends constantly to draw back the bolt 52 towards the right (Figs. 1, 3 and 7) after it has been 5 displaced.

The strength of the tension spring 46 acting upon the lever 44 as compared with the strength of the spring 53 is so chosen that the first named spring is capable of swinging the lever 44 in the 10 direction of the arrow II, and bringing it into position against the shoulder of the bolt 52, but is not capable of displacing the said bolt against the action of its spring 53. On the other hand the latter spring is sufficiently strong to enable 15 it to push the bolt 52 back against the action of the spring 46 and to swing back the lever 44 in the direction of the arrow I.

For operating the lever 44 a projecting member 20 54 is fixed laterally on the pawl carrier T (Figs. 8 and 9) of the line spacing pawl L, which latter is actuated by the line spacing lever H of the typewriter in known manner. On the said projecting member a change-over lever 55 is arranged 25 so as to be capable of swinging, the said projecting member being provided with a tapered front end projecting into the range of action of the lever arm 44a. Two lateral extensions 56a serve as limiting stops for the change-over lever 55, whilst a leaf spring 56 pressing on the rear 30 end of the change-over lever holds it firmly in the desired position, i. e. either in the position p^1 or the position p^2 indicated in full and chain dotted lines respectively in the drawings (Fig. 9). A leaf spring 57 is provided which damps the impact 35 of the spacing lever H on the pawl carrier T.

The mode of operation of the device is as follows:

Fig. 10 shows the position which the sheets occupy in the typewriter. The reference letter J denotes the journal sheet and K the somewhat smaller superposed sheet. The two sheets are provided with corresponding scales at their ends indicating the line spacing. If, now, it is assumed that the journal sheet J has been placed 45 in the machine together with the carbon paper in the manner indicated in Fig. 10, so that the fourth line from the top is typed upon, the superposed sheet K is now introduced from above in between the guide plates 8 and 9, the change-over 50 lever 55 being in the position p^2 indicated in chain dotted lines in Fig. 9, i. e. with the point located at the right of the lever 44a, the forefinger is inserted in the finger hole 4 of the apertured disc 55 29a located above the numeral 4 of the number disc and the whole control member with the disc 29a and the disc 29c is then turned in a clockwise direction (see arrow Fig. 1) until the finger strikes against the stop 30. As a result of this 60 the feed rollers 17 and 18 are turned and the superposed sheet K is drawn in and is passed around the platen up to the line 4 so that the account entry can be effected. For removing the superposed sheet it is then only necessary to 65 operate the spacing control lever H. By this operation the platen is shifted onwards to the extent of one space whilst at the same time the point of the change-over lever 55 swings the lever arm 44a of the lever 44 in the direction of the arrow II (Fig. 3) towards the left, whereby 70 the pawl 40 is swung out of the range of the pin 29d corresponding to line 4 and held in position by the pawl 40. The spring motor 37, 38 now turns the control member and also the feed rollers 17, 18 back by means of the transmission members described, so that the superposed sheet 75

K is pushed completely out again. On the attainment of the position of rest the projection 29e mounted on the disc 29c also presses the hook-shaped end 56b of the locking lever 50 upwards, so that the hook no longer holds the lever 5 44a in position (see Fig. 6). The locking lever 50 only serves the purpose of passing behind the lever arm 44a on the return movement of the control member and maintaining the said arm in engagement with the hook, as shown in Fig. 5, 10 so that the locking pawls 40 and 40h remain out of range of the pins 29d.

If it is desired to type not only on one line, but on a plurality or on all of the lines of a superposed sheet together with the journal sheet, the 15 change-over lever 55 is brought into the position p^1 (Fig. 9) with its point located to the left of the lever arm 44a. After the first entry line has been typed the spacing control lever H is operated. As 20 a consequence of this the platen together with the journal sheet J is turned onwards through a one line spacing. At the same time the lever 44 is swung by the point of the change-over lever 55 engaging its arm 44a, in the direction indicated by the arrow in Fig. 3 in such manner that 25 the locking pawl 40 is moved away from the pin 29d previously locked by it, and the locking pawl 40h is moved into the path of motion of the pins, so that it comes in front of the next succeeding pin 29d. When the line spacing lever H is released 30 the tensioned spring 46 swings the lever 44 back so that the pawl 40h moves away again from the pin retained by it and the latter is then locked by the locking pawl 40. The control member 29 and the superposed sheet K are 35 therefore likewise moved forward to the extent of a one line spacing so that the next entry is made simultaneously on the journal sheet J and the superposed sheet K on the next following line. The two locking pawls 40 and 40h operate 40 in this case in similar manner to the fixed and loose pawls of a paper carriage shifting device.

The constructional example described illustrates the arrangement as applied to a typewriter in which the line spacing lever is arranged 45 on the right hand side of the carriage. In many typewriters, however, the said lever is arranged on the left hand side of the carriage. In this latter case an operating lever for actuating the change-over lever 55 can be arranged on the left 50 hand side of the carriage and can be connected with the said change-over lever 55 by means of a linkage.

Whilst the journal sheet J is held in position 55 by the usual paper guide member P provided with pressing and feeding rollers 61 and 62, there is provided for the superposed sheet K moved by means of the feed rollers 17 and 18, below the usual paper guide member P at the lower part 60 of the paper carriage a separate paper guide member 16, in which the superposed sheet K is conveyed backwards. This arrangement renders it possible to move and to guide the journal sheet and the superposed sheet entirely independently 65 of one another without having to bring special retaining means for the individual sheets alternately in and out of the working position or to manipulate them in any other way. As a result of this a great simplification of the superposing operation is attained. The front guide plate 9 70 according to the invention is provided with a projecting part 9a, which projects downwards over the feeding rollers 17 and 18 and extends above the typed line up to a point in close proximity to the platen S. As a result of this the 75

superposed sheet K is fed up to the platen S with certainty at the height of the line to be typed and is conveyed into the separate lower paper guide member 16.

I claim:

1. In typewriters, a device for superposing and adjusting an upper sheet in front of a journal sheet located in the typewriter, comprising in combination: feed rollers arranged above the platen of the machine; a control member for feeding the superposed sheet to the right line spacing position, operatively connected to said feed rollers, said control member comprising a selector device; a spring motor comprising a housing, a spring within said housing and a cord pulley associated with said spring; a cord drum on the axle of one of said feed rollers; and a cord operatively connecting said spring motor with said cord drum.

2. In typewriters, a device for superposing and adjusting an upper sheet in front of a journal sheet located in the typewriter, comprising in combination: feed rollers arranged above the platen of the machine; a control member for feeding the superposed sheet to the right line spacing position, operatively connected to said feed rollers, said control member comprising a selector device; a spring motor comprising a spring and a housing forming a cord pulley within which said spring is arranged; a cord drum on the axle of one of said feed rollers; and a cord wound up on said cord pulley and operatively connecting said spring motor with said cord drum and said axle.

3. In typewriters, a device for superposing and adjusting an upper sheet in front of a journal sheet located in the typewriter, comprising in combination: feed rollers arranged above the platen of the machine; a control member for feeding the superposed sheet to the right line spacing position, operatively connected to said feed rollers, said control member comprising a selector device; a spring motor comprising a housing, a spring within said housing and a cord pulley associated with said spring; a cord drum on the axle of one of said feed rollers; a cord operatively connecting said spring motor with said cord drum; and a releasable locking mechanism operatively connected with said spring motor and, when in the locking position, preventing backward rotation of the latter.

4. In typewriters, a device for superposing and adjusting an upper sheet in front of a journal sheet located in the typewriter, comprising in combination: feed rollers arranged above the platen of the machine; a control member for feeding the superposed sheet to the right line spacing position, operatively connected to said feed rollers, said control member comprising a selector device; a spring motor comprising a housing, a spring within said housing and a cord pulley associated with said spring; a cord drum on the axle of one of said feed rollers; a cord operatively connecting said spring motor with said cord drum; and a releasable locking mechanism operatively connected with said spring motor and, when in the locking position, preventing backward rotation of the latter, whereby upon release of said locking mechanism, said spring motor turns said feed rollers backwards and causes the ejection of the previously introduced superposed sheet.

5. In typewriters, a device for superposing and adjusting an upper sheet in front of a journal sheet located in the typewriter, comprising in combination: feed rollers arranged above the platen of the machine; a control member for feeding the superposed sheet to the right line spacing position, operatively connected to said feed rollers, said control member comprising a selector device; stop pins arranged on the rear side of said control member; a spring motor comprising a housing, a spring within said housing and a cord pulley associated with said spring; a cord drum on the axle of one of said feed rollers; and a cord operatively connecting said spring motor with said cord drum; a releasable locking mechanism operatively connected with said spring motor and, when in the locking position, preventing backward rotation of the latter, whereby upon release of said locking mechanism, said spring motor turns said feed rollers backwards and causes the ejection of the previously introduced superposed sheet; and a setting member capable of swinging in two directions and controlling said locking mechanism in such manner that when said setting member is swung in the one direction a backward rotation of the feed rollers equivalent to one line spacing is caused and when it is swung in the other direction the locking mechanism is released whereby the feed rollers rotate backwardly under influence of the spring motor.

6. In typewriters, a device for superposing and adjusting an upper sheet in front of a journal sheet located in the typewriter, comprising in combination: feed rollers arranged above the platen of the machine; a control member for feeding the superposed sheet to the right line spacing position, operatively connected to said feed rollers, said control member comprising a selector device; stop pins arranged on the rear side of said control member; a spring motor comprising a housing, a spring within said housing and a cord pulley associated with said spring; a cord drum on the axle of one of said feed rollers; a cord operatively connecting said spring motor with said cord drum; a releasable locking mechanism operatively connected with said spring motor and, when in the locking position, preventing backward rotation of the latter, said releasable locking mechanism comprising a fixed pawl and a loose pawl co-operating with said stop pins in such manner that when said setting member is swung a step-by-step feed of the superposed sheet to the position for the typing of the next line is obtained, whereby upon release of said locking mechanism, said spring motor turns said feed rollers backwards and causes the ejection of the previously introduced superposed sheet; and a setting member capable of swinging in two directions and controlling said locking mechanism in such manner that when said setting member is swung in the one direction a backward rotation of the feed rollers equivalent to one line spacing is caused and when it is swung in the other direction the locking mechanism is released whereby the feed rollers rotate backwardly under influence of the spring motor.

7. In typewriters, a device for superposing and adjusting an upper sheet in front of a journal sheet located in the typewriter, comprising in combination: feed rollers arranged above the platen of the machine; a control member for feeding the superposed sheet to the right line spacing position, operatively connected to said feed rollers, said control member comprising a selector device; stop pins arranged on the rear side of said control member; a spring motor comprising a housing, a spring within said housing and a cord pulley associated with said spring; a cord drum on the axle of one of said feed rollers; and a cord operatively connecting said spring motor with said cord drum; a releasable locking mechanism operatively connected with said spring motor and, when in the locking position, preventing backward rotation of the latter, whereby upon release of said locking mechanism, said spring motor turns said feed rollers backwards and causes the ejection of the previously introduced superposed sheet; and a setting member capable of swinging in two directions and controlling said locking mechanism in such manner that when said setting member is swung in the one direction a backward rotation of the feed rollers equivalent to one line spacing is caused and when it is swung in the other direction the locking mechanism is released whereby the feed rollers rotate backwardly under influence of the spring motor.

ing and a cord pulley associated with said spring; a cord drum on the axle of one of said feed rollers; a cord operatively connecting said spring motor with said cord drum; a releasable locking mechanism operatively connected with said spring motor and, when in the locking position, preventing backward rotation of the latter, said releasable locking mechanism comprising a fixed pawl and a loose pawl co-operating with said stop pins in such manner that when said setting member is swung a step-by-step feed of the superposed sheet to the position for the typing of the next line is obtained, whereby upon release of said locking mechanism, said spring motor turns said feed rollers backwards and causes the ejection of the previously introduced superposed sheet; a setting member capable of swinging in two directions and controlling said locking mechanism in such manner that when said setting member is swung in the one direction a backward rotation of the feed rollers equivalent to one line spacing is caused and when it is swung in the other direction the locking mechanism is released whereby the feed rollers rotate backwardly under influence of the spring motor; and an adjustable member co-operating with the line spacing mechanism of the typewriter and adjustable into one or the other of two positions in such manner as to cause said setting member to swing in the one or the other direction.

8. In typewriters, a device for superposing and adjusting an upper sheet in front of a journal sheet located in the typewriter, comprising in combination: feed rollers arranged above the platen of the machine; a control member for feeding the superposed sheet to the right line spacing position, operatively connected to said feed rollers, said control member comprising a selector device; stop pins arranged on the rear side of said control member, a spring motor comprising a housing, a spring within said housing and a cord pulley associated with said spring; a cord drum on the axle of one of said feed rollers; a cord operatively connecting said spring motor with said cord drum; a releasable locking mechanism operatively connected with said spring motor and, when in the locking position, preventing backward rotation of the latter, said releasable locking mechanism comprising a fixed pawl and a loose pawl co-operating with said stop pins in such manner that when said setting member is swung a step-by-step feed of the superposed sheet to the position for the typing of the next line is obtained, whereby upon release of said locking mechanism, said spring motor turns said feed rollers backwards and causes the ejection of the previously introduced superposed sheet; a setting member capable of swinging in two directions and controlling said locking mechanism in such manner that when said setting member is swung in the one direction a backward rotation of the feed rollers equivalent to one line spacing is caused and when it is swung in the other direction the locking mechanism is released whereby the feed rollers rotate backwardly under influence of the spring motor; an adjustable member co-operating with the line spacing mechanism of the typewriter and adjustable into one or the other of two positions in such manner as to cause said setting member to swing in the one or the other direction; and means for detachably mounting the device on the axle of the platen of the typewriter, comprising two supporting members, pins on said supporting members, and arms fixed to the platen carriage provided with slots with which said pins come into releasable locking engagement.

9. In typewriters, a device for superposing and adjusting an upper sheet in front of a journal sheet located in the typewriter, comprising in combination: feed rollers arranged above the platen of the machine; a control member for feeding the superposed sheet to the right line spacing position, operatively connected to said feed rollers, said control member comprising a selector device; stop pins arranged on the rear side of said control member; a spring motor comprising a housing, a spring within said housing and a cord pulley associated with said spring; a cord drum on the axle of one of said feed rollers; a cord operatively connecting said spring motor with said cord drum; a releasable locking mechanism operatively connected with said spring motor and, when in the locking position, preventing backward rotation of the latter, said releasable locking mechanism comprising a fixed pawl and a loose pawl co-operating with said stop pins in such manner that when said setting member is swung a step-by-step feed of the superposed sheet to the position for the typing of the next line is obtained, whereby upon release of said locking mechanism, said spring motor turns said feed rollers backwards and causes the ejection of the previously introduced superposed sheet; a setting member capable of swinging in two directions and controlling said locking mechanism in such manner that when said setting member is swung in the one direction a backward rotation of the feed rollers equivalent to one line spacing is caused and when it is swung in the other direction the locking mechanism is released whereby the feed rollers rotate backwardly under influence of the spring motor; an adjustable member co-operating with the line spacing mechanism of the typewriter and adjustable into one or the other of two positions in such manner as to cause said setting member to swing in the one or the other direction; and means for detachably mounting the device on the axle of the platen of the typewriter, comprising two supporting members, pins on said supporting members, and arms fixed to the platen carriage provided with slots with which said pins come into releasable locking engagement.

10. A paper feed mechanism for writing machines for introducing and adjusting a paper sheet into writing position, comprising feed rollers arranged above the platen for feeding the paper sheet, a control member operatively connected with the feed rollers, and a line selector device with indications corresponding to the individual writing lines of the paper sheet, said line selector device being arranged to be actuated in connection with said control member in a quick action for introducing the paper sheet to any desired line position.

11. A paper feed mechanism according to claim 10, in which the control member and the line selector device comprise a disc with finger holes and indications for the finger holes, said indications corresponding to the different writing lines of the paper sheet.

12. A mechanism, according to claim 10, in which a motor is provided for the control member and the line selector device which is energized, upon introducing the paper sheet and de-energized to eject said sheet.

13. A device as specified in claim 10, wherein the control member and the indicating means comprise a selector disc with finger holes.

14. A device as specified in claim 10, wherein

the control member and the indicating means comprise a disc with finger holes; and a number disc above which and rigidly connected with which said first named disc is arranged and the 5 numbers of which correspond to the different lines of the account sheet.

15. A device as specified in claim 10, wherein said control member and said feed rollers, arranged above the platen, are operatively connected with a spring motor.

16. A device as specified in claim 10, wherein said control member and said feed rollers, arranged above the platen, are operatively connected with a spring motor comprising a rotatable housing, a spring within said housing fixed at the one end to the said housing and at the other end to the rigid frame of the device, and connecting means arranged between the housing and the control member and feed rollers to transfer motion from said housing to said feed rollers and vice-versa.

17. A device as specified in claim 10, wherein said control member and said feed rollers, arranged above the platen, are operatively connected with a spring motor comprising a rotatable housing constructed in the form of a cord pulley, a spring fixed at the one end to said housing and at the other end to the rigid frame of the device, a cord wound up on said housing, a cord 30 drum acted upon by said cord, and a feed roller axle upon which said cord drum is mounted.

18. A device for use on typewriters, for the introducing and adjusted superposing of an account sheet in front of a journal sheet, already 35 located in the machine, comprising in combination: feed rollers arranged above the platen; a control member operatively connected with said feed rollers; indicating means for selectively adjusting the account sheet to the desired line position; a spring motor with which said control member and said feed rollers are operatively connected; and a locking mechanism which, when in the locking position, prevents backward movement of said control member and feed rollers 40 under the influence of said spring motor.

19. A device for use on typewriters, for the introducing and adjusted superposing of an account sheet in front of a journal sheet, already located in the machine, comprising in combination: feed rollers arranged above the platen; a control member operatively connected with said feed rollers; indicating means for selectively adjusting the account sheet to the desired line position; a spring motor with which said control member and said feed rollers are operatively connected; and a locking mechanism which, when in the locking position, prevents backward movement of said control member and feed rollers 55 under the influence of said spring motor, said locking mechanism being provided with releasing means by the operation of which said spring motor moves said control member and feed rollers backwards and causes the ejection of the previously introduced account sheet.

20. A device as specified in claim 10, wherein stop pins are arranged on said control member, and a fixed pawl and a loose pawl are arranged together on a movable member and co-operate with said stop pins in such manner that when 70 said movable member is operated a backward movement of the control member and the feed rollers equivalent to one line spacing is caused.

21. A device for use on typewriters, for the introducing and adjusted superposing of an account sheet in front of a journal sheet, already 75

located in the machine, comprising in combination: feed rollers arranged above the platen; a control member operatively connected with said feed rollers; indicating means for selectively adjusting the account sheet to the desired line position; a spring motor with which said control member and said feed rollers are operatively connected; and a locking mechanism which, when in the locking position, prevents backward movement of said control member and feed rollers 10 under the influence of said spring motor, said locking mechanism being provided with releasing means by the operation of which said spring motor moves said control member and feed rollers backwards and causes the ejection of the previously introduced account sheet; step by step feeding means adapted to cause a backward movement of said control member and said feed rollers equivalent to one line spacing of the account sheet; and a universal member movable 20 into different positions to operate said releasing means and also said step by step feeding means.

22. A device for use on typewriters, for the introducing and adjusted superposing of an account sheet in front of a journal sheet, already 25 located in the machine, comprising in combination: feed rollers arranged above the platen; a control member operatively connected with said feed rollers; indicating means for selectively adjusting the account sheet to the desired line position; a spring motor with which said control member and said feed rollers are operatively connected; and a locking mechanism which, when in the locking position, prevents backward movement of said control member and feed rollers 30 under the influence of said spring motor, said locking mechanism being provided with releasing means by the operation of which said spring motor moves said control member and feed rollers backwards and causes the ejection of the 35 previously introduced account sheet; step by step feeding means adapted to cause a backward movement of said control member and said feed rollers equivalent to one line spacing of the account sheet; and a lever carrying said locking 40 mechanism, said releasing means and said step by step feeding means, said lever being capable of swinging in two directions to operate either said releasing means or said step by step feeding means.

23. A device, as specified in claim 18, wherein an adjustable part is provided on the line spacing mechanism of the typewriter, said adjustable part being adjustable into one or the other of two positions and co-operating with said line 55 spacing mechanism in such manner as to cause said universal member to move in the one or the other direction during the line spacing.

24. A device for use on typewriters, for the introducing and adjusted superposing of an account sheet in front of a journal sheet, already located in the machine, comprising in combination: feed rollers arranged above the platen; a control member operatively connected with said feed rollers; indicating means on said control member for selectively adjusting the account sheet to the desired line position, and means for detachably mounting the device on the paper carriage of the typewriter comprising releasable locking members for connecting the device with the paper 70 carriage.

25. A device for use on typewriters, for introducing and adjusted superposing of an account sheet in front of a journal sheet, already located in the machine, comprising in combination: feed 75

rollers arranged above the platen; a control member operatively connected with said feed rollers; indicating means on said control member for selectively adjusting the account sheet to the desired line position; arms fixed to the platen carriage of the typewriter and provided with slots; supporting members arranged between the device and the axle of the platen; and pins on said supporting members, said pins being releasably locked and engaging with said slots of said arms for detachably mounting the device on the platen carriage.

26. A device for use on typewriters for the introducing and adjusted superposing of an account sheet in front of a journal sheet, already located in the machine, comprising in combination: feed rollers arranged above the platen of the machine; a control member operatively connected with said feed rollers; indicating means on said control member for selectively adjusting the account sheet to the desired line position, a paper guide arranged below the platen; pressing rollers on said paper guide, for holding and feeding the journal sheet; and a separate paper guide for the superposed account sheet arranged below said first named paper guide and said pressing rollers.

27. A device for use on typewriters, for the introducing and adjusted superposing of an account sheet in front of a journal sheet, already located in the machine, comprising in combination: a feed device consisting of guide plates and feed rollers arranged above the platen; a paper guide arranged below the platen of the machine; pressing rollers on said paper guide holding and feeding the journal sheet; a separate paper guide for the superposed account sheet arranged below said first named paper guide, the front guide plate of the said feed device being prolonged below the said feed rollers up to a point in proximity to the platen above the line of writing for guiding the account sheet during its introduction from the front of the machine with certainty into said separate paper guide below said first named paper guide and said pressing rollers.

28. A device for use on typewriters, for the introducing and adjusted superposing of an account sheet in front of a journal sheet, already located in the machine, comprising in combination: a feed device arranged above the platen; guide plates and feed rollers on said feed device; a paper guide; pressing rollers on said paper guide holding and feeding the journal sheet; a separate paper guide for the superposed account sheet below said first named paper guide and said pressing rollers arranged below the platen of the machine, the front guide plate of said feed device being prolonged below said feed rollers up to a point in proximity to the platen above the line of writing for guiding the account sheet during its introduction from the front of the machine with certainty into said separate paper guide below said first named paper guide and said pressing rollers; and a movable and adjustable guiding member arranged between said feed device located above the platen and said paper guides located below the platen for separating the

two paths of the sheets above the platen from one another.

29. A paper feed mechanism for writing machines for introducing and adjusting a paper sheet into writing position, comprising feed rollers arranged above the platen for feeding the paper sheet, a control member operatively connected with the feed rollers, a line selector device with indications corresponding to the individual writing lines of the paper sheet, said line selector device being arranged to be actuated in connection with said control member in a quick action for introducing the paper sheet to any desired line position, and a spring motor operatively connected with the control member and the feed rollers, said spring motor being arranged to be drawn up at the quick introducing action of the control member.

30. In a device for use on typewriters for superposing and adjusting an upper sheet in front of a journal sheet already located in the machine, the combination of: a paper guide extending below the platen of the machine; pressing rollers arranged on said paper guide at the bottom of the platen and holding and feeding the journal sheet; and a separate paper guide for guiding the superposed sheet arranged below said first named paper guide and said pressing rollers, said separate paper guide being so arranged that the front edge thereof will receive the superposed sheet and guide it directly below and under the platen and to the rear of the typewriter.

31. In a machine of the class described, the combination with paper feed means including feed rolls, of power operated ejector devices, including a drum having connection with one of said rolls, a tape connected at one end with the source of power, at the other end with said drum and adapted to be wound upon said drum during the insertion of a paper sheet and to eject the paper upon power driven, unwinding movement.

32. A device according to claim 30, in which the separate paper guide is spaced below the first-mentioned paper guide wherein the space between the two guides is greater at the parts where the guides curve under the platen than the two end parts.

33. A device according to claim 30, in which feed rollers and feed and guide plates are provided above the printing point for guiding and feeding the superposed sheet into the separate paper guide.

34. A device according to claim 30, in which feed rollers and feed and guide plates are provided above the printing point for guiding and feeding the superposed sheet into the separate paper guide, and in which one of the guide plates is lengthened toward the platen.

35. A device according to claim 30, in which feed rollers and feed and guide plates are provided above the printing point for guiding and feeding the superposed sheet into the separate paper guide, and in which a guide plate is provided pivotally mounted to properly introduce the superposed sheet into the machine.
